UNITED STATES PATENT OFFICE.

MEYER S. HESS, OF BALTIMORE, MARYLAND, ASSIGNOR TO UNITED SHOE MACHINERY COMPANY, OF PATERSON, NEW JERSEY, A CORPORATION OF NEW JERSEY.

BOOT AND SHOE.

1,114,352.

Specification of Letters Patent. Patented Oct. 20, 1914.

Application filed November 27, 1908. Serial No. 464,542.

To all whom it may concern:

Be it known that I, MEYER S. HESS, a citizen of the United States, residing at Baltimore, in the State of Maryland, have invented certain Improvements in Boots and Shoes, of which the following description, in connection with the accompanying drawings, is a specification, like reference characters on the drawings indicating like parts in the several figures.

This invention relates to boots and shoes and more particularly to shank stiffening devices for use in the shanks of boots and shoes.

In the manufacture of boots and shoes as now carried on, it is customary to use means to stiffen the shank portion of the sole. Such stiffening means are generally incorporated between the inner and outer soles from the heel forwardly for a sufficient length to give the desired amount of stiffness to the shank of the shoe. Stiffening devices have been made of leather, of wood, of metal, and of a combination of metal 25 with leatherboard or the like. Stiffeners made of leather are entirely too expensive for ordinary use and are too pliable.

Shank stiffeners of metal or of metal and leatherboard are now very generally used and it is an object of this invention to improve shank stiffening devices of these two types.

One of the objections to metallic shank stiffeners as heretofore made, whether used with or without a backing of leatherboard or the like, has been the weight required to give the desired degree of rigidity to the metal. Increased weight involved increased cost of stock and a high cost of production and thus constituted additional objections to the use of such stiffeners.

It is therefore an object of this invention to provide a metallic shank stiffener which shall be simple and inexpensive to construct and which will afford great strength and rigidity along that portion of the shank where rigidity is desired, without the necessity of using heavy metal. This feature is of considerable importance, permitting such stiffeners to be made of relatively thin and light stock which could be easily formed

into shape by simple and high speed machines.

In the use of metallic shank stiffeners, it has heretofore been customary to secure the stiffener to the inner or outer sole by tacks, or in some instances rivets are utilized. Merely tacking the stiffener to the sole has been found to be unsatisfactory, the tacks frequently breaking and hence allowing the stiffener to work out of place, while riveting the stiffener involves too great expense and requires too much time for general use as a fastening means.

It is a further object of this invention to provide means of attaching a metallic shank stiffener to a shoe which will insure its retention in the desired position.

As herein shown in preferred forms the devices of this invention comprise pieces of thin metal curved longitudinally as may be desired for the style of shank in which it is to be used, and having one or more longitudinal ribs struck up from the body portions of such thin metal pieces, the rib or ribs standing approximately at right angles with the metal. As stiffness is desired principally in the central portion of the shank, the ribs may be limited to the central portion. This arrangement affords the advantages of rigidity incident to the angle bar or L-form of metallic construction. Preferably, and as herein shown, the ribs are formed from the body portion of the metal shank and as they are struck up from it, a rib and a corresponding aperture are made at one operation.

The metal stiffener herein shown may be used either with a backing of leatherboard, leatheroid or the like, or without such backing. In case a backing is used, it should preferably be affixed upon the side of the metal opposite to that upon which the ribs stand, it being intended that the ribs will be embedded into the material of the sole as will be described.

Other important features and details of construction will be hereinafter more particularly described and claimed.

In the drawings showing a metallic shank stiffener embodying preferred forms of the invention, Figure 1 is a view in perspective

of one form of a shank stiffener embodying the invention; Fig. 2 is a cross section on the line 2—2 of Fig. 1; Fig. 3 is a plan of the stiffener, shown in Fig. 1; Fig. 4 is a side elevation thereof; and Fig. 5 shows in perspective another form of shank stiffener embodying the invention.

Referring to Figs. 1, 2, 3, and 4, the body portion of the stiffener is designated by 1 and is preferably of thin steel and of a suitable conformation to fit the style of shoe with which it is intended to be used. The ribs 3 and 4 are formed at substantially right angles with the body portion 1 and should be approximately along the longitudinal center at about an equal distance each side of the middle line of the shank stiffener. These ribs are preferably parallel to each other and although two such ribs only are shown, a single rib or any number of ribs may be formed. These ribs may be easily constructed by cutting through the longitudinal axis of the stiffener for the desired length of rib to be formed, and turning up the resultant edges whereby the aperture 6 is simultaneously made. The stiffener could be given the proper curvature at the same operation in which the ribs are struck up. These ribs 3 and 4 may be formed either upon the upper side of the shank stiffener next the insole, or upon the lower side next the outer sole, but are preferably formed upon the upper side as herein shown. The shoulders 5 at each end of each rib are formed substantially perpendicular to the portion 1 and constitute a part of the retaining means for the shank stiffener. To incorporate this stiffener in a shoe the operator positions the stiffener upon the shank portion of the insole and secures it by means of a tack in the usual manner. Should a backing of leatheroid or the like be used, then the securing tack is ordinarily set through the backing. During the latter process of sole leveling the stiffener will be firmly affixed in the shoe, the ribs 3 and 4 being embedded in the inner sole. The stiffener being of thin material the ribs are sharp enough to be sunk into the sole by the pressure of the leveling process and the shoulders 5 will prevent longitudinal displacement.

Referring to Fig. 5 wherein is illustrated another form of the invention, 8 designates the body of the shank stiffener, having ribs 9 and 10 and shoulders 12, similar to the stiffener shown in the other figures. In this form the ribs 9 and 10 are tapered toward one end of the stiffener. The ribs may be tapered by cutting and trimming them to the taper desired after they are struck up from the stiffener, but preferably the ribs are formed to the desired taper when struck up. The latter construction may be accomplished as illustrated in Fig. 5 by converging the ribs toward each other at the tapered

ends, the amount of taper being substantially equivalent to the extent to which they are converged. Such converging of the ribs in no way interferes with embedding them in the insole. If desired, the ribs could be tapered toward each end but it is thought preferable to have these ribs tapered and correspondingly converging toward the forward end of the stiffener only. This arrangement provides a stiffener having its maximum strength or stiffness adjacent to the heel breast where such strength is required; but having less stiffness at the forward end of the shank where less strength is desired in order to enable the bending movement of the sole to be distributed over a considerable part of the sole instead of beginning abruptly at the end of the stiffener. It will be evident that, if the bending movement is concentrated at a certain part of the sole, it may unduly strain both the stock and the seams at this point.

It will be understood that the stiffener shown in Fig. 1 is made "right" and "left" while that shown in Fig. 5, having parallel sides, is interchangeable for either a right shoe or a left shoe.

Having described my invention, what I claim as new and desire to secure by Letters Patent of the United States is:

1. A shank stiffener comprising a metallic plate of relatively thin material having a longitudinal stiffening rib struck up from the middle portion of the plate and extending at substantially a right angle to the plate, said rib having a relatively sharp edge for substantially its entire length adapting it to be driven into a shoe sole.

2. A shank stiffener comprising a metallic plate of relatively thin material having a longitudinal stiffening rib struck up from the middle portion of the plate and composed of a single thickness of the material of said plate, said rib extending at substantially a right angle to the plate and having a sharp shoulder at each end thereof and a relatively sharp edge for substantially its entire length whereby it is adapted to be driven into a shoe sole.

3. A shank stiffener comprising a metallic plate of relatively thin material having two longitudinal stiffening ribs struck up from the middle portion of the plate so that they lie substantially at right angles to the plate and provide a longitudinal aperture between them, each of said ribs having shoulders at its ends and having a relatively sharp edge for substantially its entire length whereby the ribs are adapted to be driven into a shoe sole.

4. A shank stiffener comprising a metallic plate of relatively thin material having two longitudinal stiffening ribs struck up from the middle portion of the plate so that they lie substantially at right angles to the plate

and provide a longitudinal aperture between the ribs, said ribs being tapered in height from the heel end toward the forward end of the plate and converging toward the latter end and each rib having shoulders at its ends and a relatively sharp edge for substantially its entire length, whereby it is adapted to be driven into a shoe sole.

In testimony whereof I have signed my name to this specification in the presence of 10 two subscribing witnesses.

MEYER S. HESS.
